UNITED STATES PATENT OFFICE

163,275

LIQUID WARMING KITCHEN CABINET
OR THE LIKEFrederick F. Gunther, Chicago, Ill., assignor to
Helmco, Inc., Chicago, Ill., a corporation of
Illinois

Application March 3, 1949, Serial No. 1,179

Term of patent 3½ years

(CL. D81—10)

To all whom it may concern:

Be it known that I, Frederick F. Gunther, a citizen of the United States, and a resident of the city of Chicago, in the county of Cook, and State of Illinois, have invented a new, original, and ornamental Design for a Liquid Warming Kitchen Cabinet or the Like, of which the following is a specification, reference being had to the accompanying drawing, forming a part thereof.

On the drawing:

Figure 1 is a perspective view of a liquid warming kitchen cabinet or the like, showing my new design.

Figure 2 is a top plan view, and

Figure 3 is a side elevational view thereof.

I claim:

The ornamental design for a liquid warming kitchen cabinet or the like, as shown.

FREDERICK F. GUNTHER.
